STRIPING INSTRUMENT

August J. Tegethoff, Detroit, Mich., assignor to
Packard Motor Car Company, Detroit, Mich.,
a corporation of Michigan

Application March 11, 1942, Serial No. 434,167

7 Claims. (Cl. 91—62.5)

This invention relates to fluid dispensing devices, and more particularly to striping instruments.

One of the objects of the invention is to provide a fluid dispensing instrument that can be moved along a piece of work by an unskilled operator to apply a relatively wide stripe of uniform width and thickness.

Another object of the invention is to provide a plural nozzle striping instrument that will apply marginal stripes in advance of a filler stripe as it is moved along a work piece.

Another object of the invention is to provide a plural nozzle striping instrument in which a strand of wire is utilized to hold the nozzles in endwise position on their fulcrums and to also hold down the dispensing end of one of the nozzles.

Another object of the invention is to provide a plural nozzle striping instrument in which a member is utilized to limit the depression of fulcrumed nozzles and to also serve as an anchor for spring means exerting pressure to depress the dispensing ends of the nozzles.

Other objects of the invention will appear from the following description taken in connection with the drawings, which form a part of this specification, in which:

Fig. 1 is a plan view of a striping instrument incorporating the invention;

Fig. 2 is a front elevational view of the instrument applied to a piece of work;

Fig. 3 is a perspective view of the instrument;

Fig. 4 is a sectional view of the instrument taken on line 4—4 of Fig. 2;

Fig. 5 is a sectional view taken on line 5—5 of Fig. 2;

Fig. 6 is a sectional view taken on line 6—6 of Fig. 2.

Referring to the drawings by characters of reference, 10 is the main member of the striping instrument body structure on which the fluid reservoir, pump mechanisms and dispensing nozzles are carried. Shaft 11 projects from one side of the body member and fixed thereon is a roller 12 that serves to drive the shaft and to guide the instrument. The side of the body member, opposite that from which the shaft projects, is formed with a recess 13 for accommodating a series of plates 14, 15, 16 and 17 secured by screws 18, and these plates and the body member form the body structure. Plate 15 is formed with a recess that contains meshing pump gears 19 and 20 and plate 17 is formed with a recess that houses a double pump consisting of meshing gears 21, 22 and 23. Gears 19 and 21 are fixed to and driven by shaft 11.

The outer plate 14 has a fluid feeding sleeve 24 fixed to its top wall and a fluid container 25 is screwed into the sleeve. Suitable passages are

provided in the plates for feeding paint, or some similar fluid, from sleeve 24 to the recesses containing the pump gearings. The fluid is dispensed from the instrument through a plurality of nozzles 26, 27 and 28 having trailing outlet portions arranged to apply a single relatively wide stripe to a flanged work piece 29. Nozzle 26 has a hub portion 30 fixed to sleeve 31 and nozzle 28 has a hub portion 32 fixed to cap sleeve 33. These sleeves are journaled end to end on a staff 60 fixed to and projecting from the instrument body member 10 in parallel relation with shaft 11. Sleeve 33 spaces the nozzle 25 from the nozzle 28 sufficiently so that nozzle 27 can lie therebetween. Staff 60 is formed with a pair of bores 34 and 35 for feeding fluid to the nozzles journaled thereon, such passages communicating with passages 36 and 37 in the body. Gears 21 and 22 force fluid into passage 36 while gears 22 and 23 force fluid into passage 37.

Nozzle 27 has a hub portion 38 fixed to a sleeve 39 which journals on sleeve staff 40 fixed to and projecting from plate 16 in parallel relation with staff 60 but in a lower plane and forwardly thereof. The interior of staff 40 communicates with a passage 41 in plate 16 leading from the outlet side of the recess containing gears 19 and 20.

The nozzle hubs are secured on the staffs by resilient means that prevents their axial displacement. Such means is preferably in the form of a strand of wire 42 having a coiled end 43 encircling the outer end of sleeve 33 and engaged against hub 32. The wire extends parallel with the nozzle sleeves 31 and 33 and is bent to anchor around screw 44 fixed to the instrument body. The wire is bent at 45 and then coiled at 46 to encircle sleeve 39, and the end of the wire is bent over the nozzle hub 38 and fixed to the outer end of nozzle sleeve 39. This arrangement of the wire retains nozzle sleeve 39 from axial displacement on the staff and exerts torque on the sleeve normally sufficient to hold the dispensing end of nozzle 27 in contact with the work piece.

The nozzles are restricted in their downward movement by a member 50 that is fixed to and projects from the side of the body member 10 in parallel relation with the staffs and the shaft. This member can be in the form of a rod that also serves as an anchor for coil springs 51 and 52. Spring 51 is connected to pin 53 on nozzle hub 32 and spring 52 is connected by pin 54 on nozzle hub 30. Handles 55, 56 and 57 are fixed to the nozzles and extend rearwardly to overlie the member 50. The handles are so arranged that the nozzle outlet ends are in substantially the same horizontal plane when the springs engage them with member 50. Pins 58 extend through the dispensing portions of the nozzles and are located behind the outlet openings. Such pins bear against the work piece

and hold the nozzle outlets clear to dispense fluid.

The work piece 29 is formed with a pair of parallel upstanding beads 70 and 71 and the instrument is designed to apply a stripe on the intermediate surface 12. The guide wheel is arranged to roll on the work piece surface outside of bead 70, which serves as a guide therefor, and the nozzles will lie between the beads. The instrument is moved along the work piece in such relation and the guide wheel will rotate the pump shaft and thereby cause striping fluid to be moved through the nozzles onto the work piece surface in a uniform amount regardless of the speed of instrument movement.

As shown in Figs. 1 and 3, the nozzles 26 and 28 are parallel and their dispensing ends lead the outlet end of the intermediate nozzle 27 when applied to and moved over a work piece surface. The nozzles 26 and 28 will thus first apply marginal stripes on the surface over which the instrument is moved and the intermediate trailing nozzle will fill in the space on the surface between the marginal stripes. By this manner of paint application, the marginal stripes will have an opportunity to dry to some extent before the space therebetween is filled in and thus the possibility of the striping fluid running beyond the desired margins of a relatively wide stripe is reduced.

The staff 60 and spring anchor member 50 are in substantially the same horizontal plane so that the least downward pressure is exerted against the nozzles when their handles rest against member 50. The pressure is relatively light when these nozzles contact the work piece and hence the work surface will be marred a minimum extent by the frictional contact of the nozzles with the work piece surface when applying a stripe.

Although the invention has been described in connection with a specific embodiment, the principles involved are susceptible of numerous other applications which will readily occur to persons skilled in the art. The invention is therefore to be limited only as indicated by the scope of the appended claims.

What I claim is:

1. A striping instrument comprising a body, a staff extending from one side of the body, a nozzle pivotally mounted on the staff, means for feeding striping fluid from the body to the nozzle, a member projecting from the body behind the staff, a handle fixed to the nozzle and extending over the member, and a coil spring anchored to the nozzle and the member, said spring exerting a downward force upon said nozzle and said member limiting the depression of said nozzle through engagement of the handle therewith.

2. A striping instrument comprising a body, a staff projecting from one side of the body, a sleeve pivotally mounted on the staff, a nozzle having a hub portion fixed to the sleeve and a dispensing portion trailing the hub portion, means for feeding striping fluid to the nozzle, a handle fixed to the nozzle hub portion and extending above the dispensing portion of the nozzle, a member fixed to and extending from the body to the rear of the staff and below the handle, and a coil spring secured at one end to the member and at the other end to the hub.

portion of the nozzle, said spring exerting downward pressure against the trailing portion of the nozzle.

3. A striping instrument comprising a body having a recess at one side, a series of plates secured in the body recess, pump means housed by said plates, a source of striping fluid communicating with said pump means, a staff fixed to the forward end of one of said plates, a nozzle pivotally mounted on said staff, a fluid connection between the pump means and the nozzle passing through the staff and the plate to which it is fixed, spring means exerting downward pressure against the nozzle, and means limiting downward movement of the nozzle.

4. A striping instrument comprising a body, two staffs extending from one side of the body in different planes, nozzle means rotatably mounted on the staffs with their dispensing portions trailing, means for supplying striping fluid under pressure to the nozzle means through the staffs, and a strand of wire anchored to the body, the ends of the wire acting to prevent axial displacement of the nozzle means from the staffs and one end of the wire acting to urge the trailing portion of one of the nozzle means downwardly.

5. An instrument for applying a wide stripe to a work piece comprising a body, a pair of parallel staffs carried by the body, three nozzles each having a hub portion and a trailing dispensing portion, two of said nozzle hubs being rotatably mounted on one of the staffs in spaced parallel relation and the other nozzle hub being rotatably mounted on the other staff with the dispensing portion between and trailing the spaced parallel nozzles in close relationship therewith, means for feeding striping fluid under pressure to the nozzles, and means urging said nozzles toward the work piece when applied for operation.

6. An instrument for applying a wide stripe to a work piece comprising a body structure, a pair of parallel staffs projecting from the body structure and formed to feed striping fluid, one of said staffs being arranged forwardly of and below the other staff, an axle projecting from the body structure to the rear of the staffs, a pair of spaced nozzles rotatably mounted on the upper staff, a nozzle rotatably mounted on the lower staff and extending between the pair of nozzles, a guide wheel fixed on the axle, pump means in the body structure for supplying striping fluid to the staffs and connected to be driven by the axle, spring means for depressing the dispensing ends of the nozzles and means limiting the depression of the nozzles.

7. A striping instrument comprising a body, supporting means extending from one side of the body, a nozzle pivotally mounted on the supporting means, means for feeding striping fluid to the nozzle, a handle fixed to the nozzle and coextensive therewith, a stop member projecting from the body beneath the handle, and resilient means anchored to the nozzle and the member, said resilient means exerting a downward force against the nozzle and the member limiting the depression of the nozzle through engagement of the handle therewith.
